UNITED STATES PATENT OFFICE.

FREDERICK O. CARLSON, OF HOPEWELL, VIRGINIA, ASSIGNOR TO MAYHEW STEEL PRODUCTS COMPANY, INCORPORATED, OF SHELBURNE FALLS, MASSACHUSETTS, A CORPORATION OF DELAWARE.

CUTTER, MILL, OR THE LIKE.

Application filed December 3, 1925. Serial No. 73,028.

This invention relates to a new and improved cutter or mill and means and method of making cuts in the oppositely disposed faces of a tool such as pliers, wrenches or 5 the like.

It is the object of this invention, among other things, to produce a cutter or mill that will not only make peripheral cuts but also side cuts, as may be desired, and to make at 10 one and the same time these cuts in the opposite faces of the jaws of a pair of pliers, wrench or similar tools.

Referring to the drawings, in which like numerals of reference designate like parts 15 in the several figures;

Figure 1 is a side elevation of one form of my improved cutter or mill and the arbor upon which it is mounted and a pair of pliers positioned for operation thereon by 20 the cutter;

Figure 2 is a plan view thereof, the parts in section being taken generally upon line 2—2 of Figure 1;

Figure 3 is a view similar to that shown 25 in Figure 2 with a cutter or mill of different form; and

Figure 4 is a fragmentary view of the 30 face, with the cross cuts therein, of one of the jaws of a pair of pliers and a portion of another jaw connected therewith.

So far as applicant is advised, no one has heretofore produced a cutter or mill with 35 teeth upon the side faces thereof that are relieved from the cutting edges so that they actually take a cut instead of being dragged or drawn over the surface to be operated upon and remove the material by abrasion rather than cutting. Applicant has 40 designed a cutter or mill having these desired characteristics and has made possible the making of cuts in the opposing faces of the jaws of a pair of pliers, wrench or the like at one and the same time.

In the drawings, one form of my new and 45 improved cutter or mill, designated 10, is mounted upon an arbor 11, as is usual, and has a plurality of teeth 12 around the periphery thereof, from which lead grooves 13 in the sides of the cutter which may be radial, or if desired, angular or tangential, as shown 50 in Figure 1.

In this form of cutter the sides thereof, adjacent to the periphery, are provided with

rounded portions 14, and leading therefrom at an angle thereto are the side faces 55 15—15.

The grooves 13 are staggered in relation to each other upon opposite sides of the cutter (Figure 2), that is, the groove 13 upon one side of the cutter is midway between 60 two similar grooves on the opposite side of the cutter, so that in operation the teeth upon opposite sides of the cutter cut alternately, relieving the pressure upon the tool as well as the article being operated upon. 65

The outer faces of the portions 14 are provided with teeth concentric with the axis of the cutter and faces 15—15 adjacent thereto with similar teeth. These teeth are shown as being of different sizes, that is, those on the faces being smaller than those on the portions 14. Obviously, they may be of the same size or their relative sizes changed as may be desired. 70

In the form of cutter shown the side faces 75 of the teeth 12 have no teeth therein similar to those in the portions 14 and side faces 15, although they may be so provided if desired.

In the form shown in Figure 3, the cutter 16 has substantially parallel side faces, the teeth 17 therein being concentric with the axis of the cutter and staggered in relation to each other upon opposite sides thereof. 80

My improved cutter is especially effective in cutting the gripping faces of the jaws of a pair of pliers, wrench, or the like, one form of which I have shown in the drawings, wherein the jaws 18 and 19 are pivotally secured together by the stud 20, which is integral with the jaw 18. These jaws are assembled before being presented to the cutter upon a support 21 of any preferred form or shape and are moved toward each other manually, each of the opposing disposed gripping faces of the jaws synchronously engaging opposite sides of the cutter. This has not heretofore been possible, it being necessary to cut the face of each 90 jaw separately and thereafter assemble such jaws. In Figure 2, each jaw is shown with a recessed portion 22 in the face of which, cuts are made by the teeth on the portion 14, and leading therefrom toward the stud 100 20 is a substantially straight face 23, cut by 105

the teeth 12 so as to leave a straight edge thereon, which, when the jaws are closed, are utilized to cut wire or the like. By this cutter, the straight portion of the jaws 5 adjacent to the recesses 22 are provided with smaller cuts 24.

With the cutter and pliers held in the position shown in Figures 1 and 2 straight cuts are made in the face of the jaws, both 10 accurately and quickly, without the aid of jigs or other tools to rigidly hold the pliers, and both jaws are cut at one and the same time and in their permanent relative positions so that the cuts on one jaw occupy 15 a true predetermined position in relation to the cuts upon the opposite jaw, etc.

By the use of this cutter and the means 20 herein disclosed, for the purpose described, work of very high degree of perfection is produced in the minimum time and at the 25 lowest possible cost, and without the aid of tools other than the cutter itself.

In Figure 4, I have illustrated one of the 30 jaws having two cuts in the face thereof crossed in relation to each other forming a cross check jaw. This form of cutting is obtained by use of the same tools as 35 above described, by simply placing the tool first above the center of the cutter so that it will occupy the position substantially as shown by the dotted lines 25 in Figure 1, and then in the position substantially as 40 shown by the broken lines 26, that is, the jaws are pressed against the sides of the cutter at points above and below the horizontal center thereof. The cuts shown are circular but they may be made substantially straight, although not actually straight, by merely enlarging the size of the cutter.

40 The form of cutter shown in Figure 3 is designed for making the cuts in the jaws when the same are to be parallel with each

other, otherwise the cutter and mill and the means are the same as above described.

As illustrated and described herein, the 45 jaws of the tool are pressed against the opposite faces of the cutter manually, but it is obvious that this operation may be performed by mechanical means if desired, as it probably will be in tools of large size. 50

There are minor changes and alterations 55 that may be made within my invention, aside from those herein suggested, and I would therefore have it understood that I do not limit myself to the exact construction herein shown and described, but claim all that falls fairly within the spirit and scope of the appended claims.

Having described my invention, what I 60 claim as new and desire to secure by Letters Patent, is:—

1. A circular cutter having a plurality of series of cutting teeth on each side face thereof, which teeth are concentric and spaced by grooves extending from the center of the cutter toward the periphery thereof, the grooves on one side face of the cutter being staggered relative to the grooves on the opposite side face of the cutter whereby to cause alternative cutting and 70 consequent relief in pressure upon the cutter as well as upon the work. 65

2. A circular cutter having a concentric rounded portion on each side face thereof spaced from the center of the cutter, the 75 side faces of the cutter between the rounded portions and the center of the cutter being divergent relative to the center, and concentric teeth on the rounded portions and on the divergent portions. 80

In testimony whereof, I have hereunto affixed my signature.

FREDERICK O. CARLSON.
